UNITED STATES PATENT OFFICE.

GERALD DEAKIN, OF LONDON, ENGLAND, ASSIGNOR TO WESTERN ELECTRIC COMPANY, INCORPORATED, OF NEW YORK, N. Y., A CORPORATION OF NEW YORK.

AUTOMATIC TELEPHONE-EXCHANGE SYSTEM.

1,381,456.

Specification of Letters Patent. Patented June 14, 1921.

Application filed April 11, 1919. Serial No. 289,197.

To all whom it may concern:

Be it known that I, GERALD DEAKIN, a citizen of the United States, residing at London, England, have invented certain new and useful Improvements in Automatic Telephone-Exchange Systems, of which the following is a full, clear, concise, and exact description.

This invention relates to telephone exchange systems and more particularly to improvements in full automatic and semi-automatic telephone systems.

The object of this invention is to provide a new and improved arrangement of private branch telephone exchanges having a plurality of trunk lines leading from a main central office exchange, at which office so-called final or connector switches are adapted to seize any one of said trunk lines when idle. Private branch telephone exchange trunk lines are usually arranged in groups on the connector switch terminal banks and a group of such trunks leading to a particular private branch exchange is designated by a single number in the telephone directory. The connectors are adapted to be directly operated to step on to the first trunk terminals in such a group and, if the associated trunk line is busy, to automatically hunt, due to this busy condition for the first idle trunk line and extend an incoming call to the operator at the private branch exchange. Each of these trunk lines terminate at the private branch exchange in a plug that may be inserted by the operator in the jack of a private branch exchange subscriber wanted by the calling subscriber.

At night or after office hours when it is not practical to have an operator attending the private branch exchange, it is usually desirable to provide a limited number of private branch exchange lines with facilities to call the central office, and to be called by subscribers through the central office. To this end such private branch exchange lines are connected with certain trunk lines by means of the usual plug and jack and by manipulating a so-called through service key, these trunk lines and associated circuits are prepared for such through service. It is evident that under such circumstances said trunk lines must be the only ones accessible to the connector switches at the central office, that is, only the trunk lines connected directly to the private branch exchange lines

should be available for connections with outside subscribers.

In a manual private branch exchange, when a limited number of trunk lines for night service are connected for this through service, each of these trunk lines is usually identified at the central office with a number designating the private branch exchange subscriber connected thereto and the numbers listed in the telephone directory. The central office operator can therefore direct incoming calls to these private branch exchange subscribers by picking out the number of the trunk line wanted and complete the connection in the ordinary manner.

In an automatic telephone exchange, where the trunk lines leading to a private branch exchange are only accessible by means of automatic connector switches, the conditions are different and means must be provided to distinguish between such trunk lines that are connected for night service and those that are not connected. Ordinarily, the last private branch exchange trunk line in a group is provided with a low resistance path to battery in shunt with the high resistance winding of the cut-off relay so that the hunting in the group will cease at such last trunk line. If this trunk line is engaged or busy, the connector switch will send a busy signal back to the calling subscriber, but if the last trunk is idle the connector will seize it in the usual manner and extend the connection and ring the private branch exchange operator. The direct lines are similarly equipped with a low resistance path to battery and will therefore act exactly the same as the last trunk line.

One feature of the present invention provides means for rendering a plurality of private branch exchange trunk lines in a group accessible to a directly operated connector by shunting the cut-off relays of such trunks by a low resistance to battery. These trunks will thereby be available for through service in the same manner as the last trunk line in a group and the ordinary direct lines. The numbers of the private branch exchange subscribers connected for through service may be listed in the telephone directory in the same manner as ordinary subscribers except that they will be designated for night service only. When any one of these numbers is called, the connector switch will be directed by selecting impulses to the number

wanted in exactly the same manner as when a direct line is selected and the trunk line so connected will act as a direct line and the connector switch will thereby be prevented 5 from hunting in the group.

To accomplish this purpose, there is provided an automatic switch that is operated manually by the depression of a key to cut in either successively or simultaneously a 10 resistance to battery to the test terminal of each of said trunks. This key may be located either at the central office or at the private branch exchange so that the switches may be controlled either by an attendant at the central office or by the operator at the private branch exchange.

In a small private branch exchange having a limited number of trunk lines, the cutting in of resistances may be accomplished 20 by means of a relay or relays in place of the automatic switch. The usefulness of these arrangements lies in their flexibility as the switch mechanism or the relays may be easily arranged to increase or decrease the 25 number of trunk lines controlled and any one of the trunks may be selected for this service. The fact that the control may be exercised at the central office or at the private branch exchange is of considerable ad- 30 vantage.

Another feature of this invention is the provision of means whereby the ringing on incoming calls automatically ceases soon after a connector switch is set on an idle 35 trunk line but before the private branch exchange operator answers. This is accomplished by means of relays at the private branch exchange that operate in response to the ringing current to connect one of the 40 talking leads to ground for the operation of a ringing cut-off relay at the connector switch. The trunk lines will thereby be cleared for talking when the private branch exchange operator actuates her listening 45 key.

Another feature of this invention is the provision of means whereby, when the calling P. B. X. subscriber in an outgoing call hangs up and before the P. B. X. operator 50 removes the corresponding plug, the trunk line may be immediately seized by a connector switch on an incoming call and the plug end cut off to prevent ringing current from passing through to the substation. 55 This is also accomplished by means of the relays operating in response to ringing current from the connector switch. The speed in which one connection with the private branch exchange may terminate and another 60 be established is thereby considerably increased.

Another feature of this invention is the provision of means whereby the storage battery used by the trunk lines and associated 65 circuit arrangements at the private branch

exchange is charged from the central office source of direct current, whenever a trunk line is not engaged in a connection. This is accomplished by means of a battery and an adjustable resistance connected through the 70 line relay at the central office, and over the tip side of the line, through a contact of the supervisory relay and a resistance to the storage battery. The plugging through of the trunk to a private branch exchange subscriber for night service does not interfere with the charging, but the charging circuit is cut off by the supervisory relay whenever the trunk line is engaged.

This and other features of the invention 80 tending to increase the efficiency and flexibility of the private branch exchange service will become apparent in the following description.

In the accompanying drawing, Figure 1 85 represents diagrammatically an automatic telephone exchange system, a private branch exchange system and an arrangement of trunk lines as involved in this invention. Fig. 2 represents a modification of the trunk 90 line control circuit.

In the drawing, the parts designated B represent an automatic telephone exchange system such as is shown and described in the U. S. patent to Frank R. McBERTY, No. 95 1,146,583. For the final or connector switch has been substituted one having a somewhat different circuit arrangement in order to bring out clearly its connection with this invention, but as it does not as a whole form 100 a part of this invention only such of its functions as relate to the present invention, will be described; as for the remaining functions reference may be had to the above mentioned patent.

The part designated C represents an arrangement of various groups of trunk line terminals and means for rendering a plurality of trunk lines accessible to directly operated connector switches.

The parts designated D represent a private branch exchange trunk line with suitable circuit arrangement for connecting it to a private branch exchange subscriber's line indicated at E. In accordance with the 115 above-mentioned patent, the calling subscriber A, when desiring a connection with a subscriber E at the private branch exchange may, by manipulating his sending apparatus, send impulses through a line 120 finder switch 10 to a register control and sender equipment indicated at 11 at the central office, which acts as a controller to govern the subsequent selecting operations necessary to extend the connection through a 125 series of selector switches 12 and 13 and the final or connector switch 14 to a group of private branch exchange trunk lines.

It will be assumed that an ordinary day 130 service call is to be set up and that all the

- selecting impulses have been sent to extend a connection to the connector switch and that the connector has been operated to its hunting stage; that is, the brushes of the connector have arrived at the beginning of a group of private branch exchange trunk line terminals indicated in the dotted enclosure 20, and that the hunting for an idle trunk line is to begin. Inasmuch as the operations up to this stage are exactly identical with the corresponding operations in the above-mentioned patent, it is assumed that the description of the operation of the connector switch from this stage on and the subsequent operations necessary to extend the incoming call to a called subscriber at the private branch exchange will be sufficient to clearly understand the invention involved.
- 20 The trunk-hunting operations of the connector switch begin when the sequence switch 100 arrives in position 6, in which position the line relay 25 is permitted to be deenergized. The selector switch B has access to direct subscribers' lines, such as line 32, and also to private branch exchange trunk groups, one of which is shown consisting of the trunks 33, 34 and 30. When the brushes of the selector switch are advanced to the first trunk 33 of an exchange group, and such trunk is busy, the switch is arranged to determine this fact and to continue to hunt over the succeeding trunks in search of an idle one. The cut-off relays, such as relay 102, of all trunks preceding the last trunk 30 of an exchange group are provided with a high resistance winding. If the first trunk of the group is busy, the potential on the test terminal, applied through the high resistance winding of relay 102, is reduced to such an extent that the test relay 35 cannot operate to discontinue the movement of the selector switch in the manner described in detail hereinafter.
- 40 Consequently, the switch advances to the next trunk, and so on, until an idle one is found, or until it reaches the last trunk 30 in the group. The switch will stop on the terminals of this trunk regardless of the busy or idle condition thereof. To accomplish this feature the winding of cut-off relay 44 is shunted by a low resistance 43. Due to the low resistance 43, sufficient potential exists on the test terminal 45, even though the trunk is already engaged to permit the energization of test relay 35. Relay 35 consequently becomes operated and terminates the hunting movement of the selector switch. The sequence switch 100, as hereinafter explained, advances through position 8, in which position a test is made to determine the busy or idle condition of the trunk 30. If the trunk is idle, full potential exists on terminal 45, and the test relay 57 is operated through its high resistance winding to control the sequence switch 100 in a manner to seize and apply ringing current to the trunk line. If, however, the trunk is busy, the potential on the test terminal 45 is so reduced, notwithstanding the low resistance shunt 43, that relay 57 cannot operate and the sequence switch 100 is controlled in a different manner to bring about the release of the selector switch and the application of a busy tone back on the calling line. Should one of the first trunks in the group, such as trunk 33, be idle when a test thereof is made, full battery potential is applied through the winding of cut-off relay 102, and the test relay 35 attracts its armature to determine the hunting movement of the selector switch B.
- 45 Considering the direct subscriber's line, indicated at 32, the cut-off relay 101 thereof is provided with a comparatively low resistance winding. In other words, the resistance of relay 101 corresponds to the combined resistance of cut-off relay 44 and resistance 43 associated with the last trunk of a private branch exchange group. Consequently, when the brushes of the selector switch are advanced to the terminals of a subscriber's line, such as line 32, the switch does not perform a hunting movement even though the line may be busy at the time. 95 Whether busy or idle, the potential on the test terminal of a direct line is always sufficient to cause the energization of test relay 35, which, as will be seen later, is what brings about the termination of the hunting movement of the selector switch.
- 50 It will be assumed that all of the trunk lines in group 20 are busy except the last and the brushes 29 of the connector switch will therefore eventually land on the terminals 30 of the last trunk line 31. As the connector finds the trunks 32, 33 and 34 busy, the private branch exchange relay 35 will not be energized and a circuit for the power magnet 36 will be established as soon as the armature of line relay 25 reaches its back contact. This power circuit extends from battery, power magnet 36, upper contact of sequence switch contact 38, back contact and armature of relay 40, back contact and armature of relay 25, to ground. This circuit keeps the power magnet energized and the brushes of the switch are advanced over these busy trunk line terminals until they finally land on terminals 30, when a circuit is established from battery 42, resistance 43 in parallel with battery and cut-off relay 44, through terminal 45, brush 46, private branch exchange relay 35, lower contact of sequence switch contact 48, to ground. 110 This energizes relay 35 and establishes a circuit from battery, resistance 50, armature and front contact of relay 35, test relay 40, front contact and armature of relay 52, to ground, as relay 52 is held up as long as the 130

connector switch is engaged. Test relay 40 energizes and breaks the above-mentioned power circuit so that the power magnet 36 deenergizes and stops the switch. The energization of the test relay 40 establishes a circuit from battery, sequence switch 100, upper contact of sequence switch contact 54, front contact and armature of relay 40, back contact and armature of relay 25, to ground, and a branch circuit from battery, holding magnet 55, lower contact of sequence switch contact 56, to ground, over the same circuit. The holding magnet 55 energizes to assist in the stopping of the switch 10 and the sequence switch 100 is moved out of position 6 toward position 12 and will arrive there if the line is idle but stop in position 10 if the line is busy. As it was assumed that this trunk line was idle, the test relay 20 57 will be energized when the sequence switch passes through position 8 by a circuit established from battery 42, resistance 43, terminal 45, brush 46, high resistance winding of relay 57, upper contact of sequence switch contact 48, to ground, and establish a locking circuit for itself through its low resistance winding, front contact and armature, test relay 40, front contact and armature of relay 52, to ground. In 30 this manner relay 40 is held energized, and as the sequence switch contact 54 is closed through positions 6 to 11, the sequence switch will advance to position 12.

In position 12 ringing current is applied 35 from alternating current ringing source 58, upper contact of sequence switch contact 59, brush 60, terminal 61, contacts of dialing key 62, retardation coil 63, condenser 64, trunk line relay 65, contacts of dialing key 40 62, terminal 66, brush 67, lower contact of sequence switch contact 68, ringing relay 69, to battery. This circuit operates trunk line relay 65, which relay locks up over a circuit from battery 325, battery 45 cut-off key 95, trunk line cut-off relay 70 and holding winding of the relay 65 and its front contact and armature, to ground at a contact of listening key 72. This holding circuit energizes the cut-off relay 50 70, which relay cuts off the trunk leads to listening key 72 and extends the trunk leads through a condenser 71 and relay 73. Relay 73 is energized over the same circuit as relay 65 and relay 73 applies at its front contact 55 and armature a ground to the tip side of the line. This ground completes a direct current circuit for the ringing relay 69 from battery, ringing relay 69, lower contact of sequence switch contact 68, brush 67, terminal 66, contacts of dialing key 62, upper armature and front contact of cut-off relay 70, to ground at the front contact and armature of relay 73, to energize ringing relay 69 which did not respond to the above-mentioned ringing current. The energization of

ringing relay 69 completes a circuit from battery, sequence switch 100, upper contact of sequence switch contact 74, front contact and armature of ringing relay 69, to ground, to drive sequence switch 100 out of position 70 12 and into position 15.

Position 15 is the talking position in which the ringing current is cut off and the talking leads are cut through as far as the trunk line cut-off relay 70 in readiness for 75 the operation of the listening key. As soon as the ringing current is cut off, the relay 73 deenergizes to remove the ground from the tip side of the line in order that there may be no drain on the battery 75 after the 80 ringing period, which is practically instantaneous. When the trunk line relay 65 was locked up, a branch circuit from battery, relay 76, trunk line lamp 77, the front contact and armature of relay 65, to ground at 85 the listening key 72 was completed and lamp 77 lighted to indicate to the private branch exchange operator that an incoming call was present on this trunk line. The operator then depresses the listening key 72, the immediate effect of which is that trunk line relay 65 and cut-off relay 70 are released and the talking leads extended through to the operator's telephone. The depression of the listening key 72 also establishes a circuit 90 from battery, relay 82, to ground at the listening key 72. This energizes relay 82 and a circuit is established from battery, armature and back contact of supervisory relay 83, outer armature and front contact of relay 82, supervisory lamp 84, to ground to light this lamp for supervisory purposes as hereinafter described. The operation of relay 82 also establishes a shunt circuit across the talking leads through retardation coil 105 63, through-service key 85, inner armature and front contact of relay 82. This shunt circuit is used for metering purposes that forms no part of this invention and need not be further described.

110 The private branch exchange operator is now in a position to ascertain the number of the private branch exchange subscriber wanted by the calling subscriber and when the number is obtained she inserts a plug 78 115 in jack 79 of the called subscriber at E and before she restores the listening key 72, so as to retain the relay 82 energized over a circuit through the sleeve of the plug and jack to ground and keep the supervisory lamp 84 120 lighted. If the subscriber at E is free, the operator depresses her ringing key 86 and rings until the called subscriber answers. When the called subscriber answers, a talking circuit is completed through supervisory 125 relay 83 and the circuit for supervisory lamp 84 is broken thereby extinguishing the lamp.

130 At the end of the conversation and when the called subscriber hangs up his receiver,

- the supervisory relay 83 is deenergized so that the supervisory lamp 84 again lights to notify the operator that the conversation has been discontinued. The operator then 5 removes the plug 78 from jack 79 and this permits relay 82 to deenergize which deenergization extinguishes the supervisory lamp 84 and removes the shunt across the trunk line talking leads. This removal of 10 the shunt circuit permits the connector switch to be released when the calling subscriber hangs up, which act results in the deenergization of relay 52, as is fully described in the aforementioned patent. 15 The deenergization of relay 52 establishes a circuit from battery, sequence switch 100, upper contact of sequence switch contact 56, back contact and armature of relay 52, to ground, to move sequence switch 100 out 20 of position 15 into position 17. In position 17, a circuit is established from battery sequence switch 100, lower contact of sequence switch contact 54, back contact and armature of relay 25, to ground, to move 25 sequence switch 100 into position 18. In position 18 a circuit is established from battery, power magnet 36, upper contact of sequence switch contact 38, back contact and armature of relay 40, back contact and 30 armature of relay 25, to ground, to operate power magnet 36 and drive the connector switch back to normal position. On reaching normal position, a circuit is established from battery, relay 25, upper contact of sequence switch contact 89, normal contact 90, to ground. Relay 25 energizes and establishes a circuit from battery, sequence switch 100, upper contact of sequence switch contact 74, and front contact and armature of 35 40 relay 25, to ground, to drive sequence switch 100 back to position one.

In preparing the private branch exchange trunk lines for night service, that is, making a number of trunks accessible for incoming calls, it is only necessary to convert them to direct lines by inserting a low resistance shunt path to battery in parallel with the high resistance cut-off relay winding to battery. The trunks that are to be used for night service are then connected with the private branch exchange subscribers who are to receive or send calls directly during the absence of the private branch exchange operator. In order to prevent the trunk lines from being cut off from the connected private branch exchange subscribers by relay 70 in the manner heretofore described when seized by the connector switch, the through service key 85 and battery cut-off key 95 are operated.

A trunk line 32 in the group of trunks at 20 is typical of the ordinary trunk line and trunks 33 and 34 are typical of the trunk lines to which a resistance shunt may be added. By switching in these resistances

on trunks 33 and 34, or any other trunk in the group, such trunks will be made available for through service. A sequence switch 200 is used for this purpose having sequence switch contacts, such as 201 and 202, 70 closed in positions 2 to 18, 4 to 18, etc., a normal contact 203 closed just after position 1 to just before position 18, and a contact 204 closed in position 1 and position 18. To control the sequence switch 200, key 206 at 75 the private branch exchange and the relay 208 at the central office, are provided. To cut in resistances, the private branch exchange operator depresses key 206 and a circuit is established from battery, relay 208, key 206, to ground. This energizes relay 208 and a circuit is established from battery, sequence switch 200, upper contact of sequence switch contact 204, front contact and armature of relay 208, to ground. 80 This starts the sequence switch 200 which completes a circuit for itself through its normal contact 203, to ground, and continues to move or rotate until it reaches the eighteenth position when the circuit is broken and the sequence switch stops. The rotation of sequence switch 200 from position 1 to 18 cuts in the resistance 210 in position 2, resistance 211 in position 4, etc. 85 The resistances 210 and 211 are equal in value to that of resistance 43. Hence, for example, when resistance 210 is placed in shunt around the winding of relay 102 the electrical condition on the test terminal of trunk 33 is changed to conform exactly with that on the last trunk 30 of the group. Consequently, when the brushes of the selector switch B are advanced to terminals of trunk 33, relay 35 is operated whether or not the trunk is busy at the time. In this manner 90 the selector switch may be positioned on the terminals of the trunk, which, for night service, leads directly to a subscriber's line in the private branch exchange and is not caused to hunt uselessly over succeeding trunks in the group in case the subscriber's line is busy. Resistance 211 accomplishes the same purpose with respect to the next trunk 34. It is evident that all the resistances could be inserted at once but it is often preferable to switch them in succession. Selection of trunks for night service need not be confined to the trunks 33 and 34 and need not be made in any particular order as the trunks selected may be scattered over the group by removing sequence switch contact, such as 201 or 202, or by 105 the addition of others.

In Fig. 2 is shown a key 215 that may be substituted for key 206 and relay 208 and the leads 216 and 217 may be connected at 110 218 and 219, respectively, to the sequence switch contact 204, in case the control over the night service is to be exercised by an attendant, such as wire-chief at the central 115 120 125 130

office instead of by the private branch exchange operator.

The groups of trunks shown at 21 are representative of a small private branch exchange group in which the resistances 220 and 221 of trunks 222 and 223 may be cut into circuit by means of a relay 225 that is controlled by means of a key 226 located at a private branch exchange station having only 10 a limited number of trunk lines and in which night service is confined to two or three trunks.

It is seen by this arrangement of the night and through service that no hunting will 15 take place at the connector switch but that the connectors will be directed to a particular private branch exchange trunk by means of selective impulses in the same manner as to a direct line and that there will be no distinction 20 between a private branch exchange trunk line connected to a private branch exchange subscriber and the line leading directly to a regular subscriber. The relay 35 will immediately be energized when the 25 brushes of the connector are set on a selected private branch exchange trunk, and as hereinbefore described, the sequence switch will be driven toward the twelfth position. In case the line is idle, the call will proceed, as 30 already described, but in case the wanted subscriber is busy, the sequence switch 100 will stop in position 10, for it will be remembered that it depends on the energization 35 of relay 57 for maintaining the relay 40 operated after the sequence switch passes the eighth position. Therefore, in case the 40 line is busy, the relay 57 will not be energized as there will be a low resistance path to ground through the test relay 57 of the 45 connector already connected to a multiple of the test terminals of this trunk. This path to ground is of low enough resistance to prevent a sufficient current from flowing through the high resistance winding of relay 57 of this connector. Consequently, the 50 sequence switch 100 will stop when it arrives in position 10 as the relay 40 that was deenergized already in the eighth position, has broken the energizing circuit for the sequence switch 100 at its front contact and armature. In position 10, a busy tone is sent back to the calling subscriber through induction coil 250, the primary circuit being established from busy tone alternating current source 251, upper contact of sequence switch contact 252, primary circuit of induction coil 250, to ground. When the calling subscriber hangs up, due to this busy tone, relay 52 deenergizes and a circuit is established 55 from battery, sequence switch 100, upper contact of sequence switch contact 56, back contact and armature of relay 52, to ground, to move sequence switch 100 into position 11. In position 11, a circuit is 60 established from battery, power magnet 36,

upper contact of sequence switch contact 38, back contact and armature of relay 40, back contact and armature of relay 25, to ground, to drive the connector switch back to normal. When reaching normal position, a circuit is established from battery, relay 25, upper contact of sequence switch contact 89, normal contact 90, to ground. Relay 25 is energized and establishes a circuit from battery, sequence switch 100, upper contact of sequence switch contact 74, front contact and armature of relay 25, to ground, to move sequence switch 100 out of position 11 and into position 12. In position 12, a circuit is established from battery, sequence switch 100, upper contact of sequence switch contact 56, back contact and armature of relay 52, to ground, to drive sequence switch 100 into position 17. In position 17, a circuit is established from battery, sequence switch 100, lower contact of sequence switch contact 54, back contact and armature of relay 25, to ground, to drive sequence switch 100 into position 18. In position 18, a circuit is established from battery, relay 25, upper contact of sequence switch contact 89, normal contact 90, to ground, to again energize relay 25 and establish a circuit from battery, sequence switch 100, upper contact of sequence switch contact 74, front contact and armature of relay 25, to ground, to drive sequence switch 100 out of position 18 into normal position.

In a call outgoing from a private branch exchange, the private branch exchange subscriber, by removing his receiver from the hook, lights the lamp 301 and the operator answers by inserting plug 78 in jack 79 which extinguishes the lamp 301. The operator then operates listening key 72 and ascertains the number of the subscriber wanted. The dialing of a number may be done by the private branch exchange operator by operating dialing key 62 which connects the operator's sender 305 to the trunk line 100 and the retardation coil 306 to the plug end of the trunk line. When the operator has finished dialing the number, the dialing key returns to normal and the connection which has proceeded automatically through a line 105 finder indicated at 310 at the central office is extended to the wanted subscriber in the usual manner.

When the trunk lines are prepared for through or night service that are connected 120 to certain private branch exchange subscribers and the through service key 85 is operated, outgoing calls may be made by these private branch exchange subscribers by means of an automatic sender of the usual type 125 indicated at 300. The connection to a wanted subscriber is set up and controlled by the private branch exchange subscriber in the same manner as by the private branch exchange operator and, as hereinbefore de- 130

scribed, the release of the connector is controlled by the hanging up of the calling private branch exchange subscriber's receiver.

- 5 The circuit for charging of the storage battery at 325 extends from battery 75, adjustable resistance 326, line relay 327, tip side of trunk line 31, contact of dialing key 62, upper armature and back contact of cut-off relay 70, outer back contact and armature of relay 82, armature and back contact of relay 83, resistance 329, key 330, battery 325 to ground. The charging of the battery is not interfered with at any time, except 15 when the truck circuit is engaged, when the supervisory relay 83 is energized and breaks the battery circuit at its armature and back contact. The plugging up of the trunk line for night service has no effect on the battery 20 charging circuit, as only the battery cut-off key 95 is operated to cut off the battery from relays 70 and 82, trunk lamp 77 and alarm relay 76.

What I claim is:

- 25 1. In a telephone exchange system, subscribers' lines, trunk lines, an automatic switch for selecting any of said lines, means for placing a given electrical condition on said subscribers' lines, means for placing a 30 different electrical condition on the trunk lines, means responsive to said electrical conditions for controlling the operation of said automatic switch, and means for automatically changing the condition on said trunks 35 to correspond to the electrical condition on said subscribers' lines to render said trunks of the same identity as the subscribers' lines.

2. In a telephone exchange system, subscribers' lines, trunk lines, an automatic 40 switch for selecting any of said lines, means for placing a given electrical condition on said subscribers' lines, means for placing a different condition on the trunk lines, means responsive to said electrical conditions for 45 controlling the operation of said switch, and an auxiliary switch for changing the condition on said trunks to correspond to the condition on the subscribers' lines to render said trunks of the same identity as the subscribers' lines.

3. In a telephone exchange system, subscribers' lines, an operator's position, trunk leading to said position, an automatic switch for selecting said lines and trunks, means 55 for placing a given electrical condition on said lines, means for placing a different condition on said trunks, means responsive to said electrical conditions for controlling said switch, and means controlled manually by 60 the operator for changing the condition on said trunks to correspond to the condition on said lines to render said trunk and lines of the same identity.

4. In a telephone exchange system, sub- 65 scribers' lines, trunk lines normally distin-

guished from the subscribers' lines, a switching device operable to engage any one of said lines, automatic means at one end of the trunk for eliminating the normal distinction between a trunk and a subscribers' line 70 whereby said trunk may be engaged as a subscribers' line, and means at the other end of said trunk for controlling said automatic means.

5. In a telephone exchange system, subscribers' lines, trunk lines normally distinguished from the subscribers' lines, a switching device operable to engage any one of said lines, automatic means for eliminating in succession the normal distinction between 80 said trunks and subscribers' lines whereby said trunks may be engaged as subscribers' lines, and manual means for controlling said automatic means.

6. In a telephone exchange system, a plurality of trunk lines interconnecting two telephone exchanges, a switching device operable to engage any one of said trunks, means at said switching device for applying ringing current to a trunk, and means at the 90 distant end of a trunk for completing a circuit including only one of the talking leads of said trunk to disconnect the ringing current.

7. In a telephone exchange system, a plurality of trunk lines interconnecting two telephone exchanges, a switching device operable to engage any one of said trunks, means for applying ringing current to a trunk, means at the distant end of a trunk 95 responsive to said ringing current, and means controlled from said responsive means over one side of the talking leads of the trunk to disconnect said ringing current.

8. In a telephone exchange system, a plurality of trunk lines interconnecting two telephone exchanges, a switching device operable to engage any one of said trunks, means for applying ringing current to a trunk, means at one exchange for disconnecting the ringing means, means at the other exchange responsive to said ringing current, and means at said second exchange controlled by said ringing responsive means to operate said ringing disconnecting means 110 over one side of the talking leads of the trunk.

9. In a telephone exchange system, a plurality of trunk lines interconnecting two telephone exchanges, a switching device operable to engage any one of said trunks, means for applying ringing current to a trunk, a relay at one exchange for disconnecting the ringing means, a relay mechanism at the other exchange responsive to 120 said ringing current, and means operated by said relay mechanism for connecting a ground over one side of talking leads to control the ringing relay.

10. In a telephone exchange system, a plu- 130

- rality of trunk lines interconnecting two telephone exchanges, a switching device operable to engage any one of said trunks, means for applying ringing current to a trunk, means for connecting a subscriber at the distant end of a trunk, and automatic means responsive to the ringing current for cutting off the subscriber from the trunk during the ringing period.
- 10 11. In a telephone exchange system, a plurality of trunk lines interconnecting two telephone exchanges, a switching device operable to engage any one of said trunks, means for applying ringing current to a trunk, an operator's position at the distant end of a trunk, automatic means responsive to the ringing current for cutting off the op-

erator's position from the trunk, and a manual means for restoring the connection to the operator's position. 20

12. In a telephone exchange system, a plurality of trunks interconnecting two exchanges, a switching device operable to engage any one of said trunks, a charging means including an adjustable resistance and a source of direct current at one exchange, an adjustable resistance and storage battery at the other exchange, and a circuit interconnecting said batteries over one talking lead of a trunk. 25

In witness whereof, I hereunto subscribe my name this 12th day of February, A. D., 1919.

GERALD DEAKIN.
